Lebbeus Hill,
by Crosby Gregory. *Atlys.*

UNITED STATES PATENT OFFICE.

LEBBEUS HILL, OF LYNN, MASSACHUSETTS.

DESIGN FOR A BOOT OR SHOE HEEL.

SPECIFICATION forming part of Design No. 25,187, dated February 18, 1896.

Application filed January 13, 1896. Serial No. 575,383. Term of patent 7 years.

To all whom it may concern:

Be it known that I, LEBBEUS HILL, a citizen of the United States, residing at Lynn, county of Essex, State of Massachusetts, have 5 invented a new and original Design for a Boot or Shoe Heel, of which the following is a specification, reference being had to the accompanying drawing, forming a part thereof.

The drawing is a perspective view of a heel 10 illustrating my design.

The leading feature of my design consists in a tapering body—that is, a body made larger at one side or face than at its opposite side or face, the latter or smaller side or face 15 presenting an outline substantially like that of the conventional heart.

Referring to the drawing, the body *a* is made tapering—that is, is larger at its face or side marked *a'* than at its face or side

marked *a''*, and the latter or smaller face 20 presents in outline the two semicircular or scalloped lines *a³* abutting at their adjacent ends and having their opposite ends swept about in curved lines *a⁴* to the edge of said face which is opposite the curved lines *a⁵ a⁶*, 25 thus presenting an outline like that of the conventional heart.

I claim—

The design for a heel for boots or shoes substantially as herein shown and described. 30

In testimony whereof I have signed my name to this specification in the presence of two subscribing witnesses.

LEBBEUS HILL.

Witnesses:

JOHN C. EDWARDS,
FREDERICK L. EMERY.
